UNITED STATES PATENT OFFICE

ULINORE LE DOUX, OF BREAUX BRIDGE, LOUISIANA

VAULT

Application filed July 19, 1929. Serial No. 379,492.

The primary object of this, my present invention is to provide a burial vault adapted for the reception of a casket and which includes a body, a bottom and top formed of reinforced concrete slabs and shaped in a manner whereby the said slabs may be easily associated to provide a complete vault and also wherein the slabs when separated may be shipped from the factory in a knockdown condition which will afford a small package.

With these general objects in view the invention consists in the combination and arrangement of parts hereinafter described and in which like characters of reference designate corresponding parts throughout the several views.

In the drawings:

Figure 1 is a substantially central vertical longitudinal sectional view through a vault in accordance with this invention.

Figure 2 is an inverted plan view of the top slab.

Figure 3 is a sectional view approximately on the line 3—3 of Figure 1.

Figure 4 is a transverse sectional view approximately on the line 4—4 of Figure 1.

Figure 5 is a fragmentary plan view looking toward one of the corners of the vault with the top slab removed.

The slab that constitutes the bottom of the vault is indicated by the numeral 1. This slab is reinforced by longitudinally arranged rods 2, embedded therein in the process of molding and is further reinforced with wire mesh 3 arranged both above and below the rods 2. The bottom slab, adjacent to its edges is formed with both longitudinal and transverse grooves 4, respectively, and the side walls provided by these grooves are arranged at outward angles. The grooves communicate with substantially square or rectangular pockets 5 and 6 at the opposite corners of the slab 1. The side walls provided by these pockets are also beveled but the inner or confronting walls provided by the pockets

6 are straight, as indicated by the numerals 7. The inner walls of the transverse grooves 4, at their juncture with the inner walls of the longitudinal grooves of the bottom slab 1 are widened, as indicated in the drawings by the 50 numeral 8.

The side slabs are indicated by the numerals 9 and the end slabs by the numerals 10 and 11 respectively. These slabs have embedded therein longitudinally extending reinforcing rods 12 and vertically disposed but also longitudinally extending reinforcing wire mesh plates 13 arranged at the opposite sides of the rods 12, and both the upper and lower edges of the side and end slabs are 60 beveled, as at 14, whereby the lower ends of the said slabs may be received in the groove of the bottom slab. The corners of the side slabs are thickened and are of substantially square formation, as indicated by the numerals 15 and 16, respectively. The corners 65 15 and 16 have embedded therein vertically disposed reinforcing rods 17 and the upper and lower edges of the widened corners are beveled whereby the lower portions of the 70 corners will be received in the pockets 5 and 6. The corner portions 14 of the side slabs have their confronting faces straight but merge into angular vertically arranged shoulders 18, while the confronting faces of the 75 corners 15 of the said side slabs are grooved and the side walls provided by the grooves are beveled. These grooves for distinction are indicated by the numeral 19 and are designed to receive therein the beveled corners 80 20 on the vertical ends of the end slab 10.

The end slab 11 has its upper and lower edges beveled transversely but its ends are straight, so that the same can be inserted in the groove 4 at one end of the bottom 85 slab and sealed by plastic material to the remainder of the vault after the bottom, the sides and the end 10 have been assembled and also after the top hereinafter to be described has been arranged upon the vault. By this 90

arrangement it will be noted that a casket may be delivered through the end thereof closed by the slab 11.

The top slab is indicated by the numeral 21, the same having its outer face arched transversely, as at 22. This slab is also provided with longitudinal reinforcing rods and with wire mesh reinforcements arranged above and below the said rods. The center 10 of the top slab 21 from the under face thereof is concaved longitudinally, as at 22, from points adjacent to the sides and ends of the said top slab. In the process of molding the concaved wall is reinforced by a central 15 longitudinal rib 23 and by transverse spaced ribs 24. By concaving the inner face of the slab the weight of the same is materially decreased and by providing the said concavity with the reinforcing rib the strength 20 of the top slab is not impaired by the said concavity. The under face of the slab is provided, adjacent to its edges with longitudinal grooves 25 which are intersected by transverse grooves 26. The side walls 25 provided by these grooves are beveled and the grooves at the corners of the said top slab are widened providing the same with substantially square or rectangular pockets 27 whose side walls are also beveled. Thus 30 the grooves 25, 26 and 27 snugly receive therein the beveled edges at the top of the side and end slabs and likewise the beveled edges at the thickened corners of the side slabs. It is, of course, to be understood that 35 the slabs constituting the improvement are secured together by suitable plastic material which, of course, is poured into the grooves provided by the said slabs. The rods 17 at the corners of the side slabs project a slight distance above the top of the 40 said slabs and the end slabs have longitudinally arranged reinforcing wires 26 therein whose ends are wound around and secured to the projecting portions of the said rods 45 17 this, of course, being accomplished before the top slab is arranged upon the body of the vault.

If desired, the bottom slab may be dispensed with so that the body and top will 50 serve as a receptacle for a casket and it is thought that the foregoing description when read in connection with the accompanying drawings will fully set forth the construction and advantages of the improvement so 55 that further description will not be required.

Having described the invention, I claim:

A burial vault formed of reinforced concrete slabs to provide a body that comprises 60 sides and ends, a top and a bottom, said top and bottom slabs being grooved longitudinally and transversely adjacent to their edges, and the grooves in the corners of said slabs being enlarged, the side slabs being grooved vertically to receive the ends of the 65 end slabs therein, and the corners of the

side slabs being thickened to conform to the enlarged grooves of the top and bottom slabs, the confronting faces of the thickened corners at one end of the side slabs of the body being straight, and the ends of the end slab 70 to be received between such corners being likewise straight to permit the last mentioned end slab to be placed in position after a casket has been placed within the body of the vault.

In testimony whereof I affix my signature. 75
ULINORE LE DOUX.
